UNITED STATES PATENT OFFICE.

FREDERICK C. KEIGHLEY, OF UNIONTOWN, PENNSYLVANIA.

MINE-ROOF SUPPORT.

No. 875,182.

Specification of Letters Patent.

Patented Dec. 31, 1907.

Application filed October 16, 1907. Serial No. 397,625.

To all whom it may concern:

Be it known that I, FREDERICK C. KEIGHLEY, a citizen of the United States, residing at Uniontown, in the county of Fayette and State of Pennsylvania, have invented a new and useful Mine-Roof Support; and I do hereby declare the following to be a full, clear, and exact description of the invention, such as will enable others skilled in the art to which it appertains to make and use the same.

This invention pertains to mines generally, but more especially the invention resides in a new, useful and novel device, designed for supporting the roof measures in coal and other mines, or, in other words, the roofs of rooms or headings, which are cut through the body of the coal or ore, and substantially at right angles to the shaft of the mine, through which ingress and egress is had to the mine workings, and from which rooms or headings, the coal or ore is removed, and elevated to the surface of the earth by means of elevators, which are usually disposed within the shaft of a mine, as will be hereinafter clearly manifest.

In its broadest aspect, the invention aims as an essential object to provide a device of this character which comprises essential features and elements of construction, which features and elements consist of standards, posts or legs, placed adjacent to the longitudinal side walls of a room or heading of a mine, to the upper ends of which, and transversely of the room, the tie rods, or stretchers, of any suitable metal are attached, by means of loops, different constructions of which are shown in the detail views of the drawings; these tie rods or stretchers and standards or posts are placed from two to four feet apart, as may be desired, and which tie rods or stretchers support the timbers, (lagging or forepoling, as termed in mining language), which are placed parallel with the length of the room or heading of the mine.

The invention directs as a further object to dispose the standards or posts, so as to allow them to diverge outwardly at the top, the object of which is to take advantage of the fact that when the weight is placed upon the tie rods or stretchers, by the timbers or lagging, the tendency thereof will be to draw the posts together, thus making an unusually strong roof support, as will be clearly observed in the drawings. The diverging of the standards or posts accomplishes another

object, for instance, much of the timber used in coal and other mines for supporting the roof thereof, in the usual manner, is broken very often by the expansion of the roof measures; this device or apparatus will allow the roof to expand, without breaking the supporting device, as there will be enough give, stretch or elasticity, in either rods or wire rope, so as to allow for full expansion of the rocks. In ordinary practice, the standards or posts diverge from each other, at the bottom thereof, and their upper ends receive a cross bar; this construction of support has been found to be impracticable for supporting the roof measures.

The invention aims, by diverging the standards or posts at their upper ends, as a further object, to provide means by which the tie rod or stretcher, disposed at the top of the standards or posts, are drawn taut, by a sufficient amount of pressure against the lower portions of the standards or posts, the tendency of which pressure being outwardly, will, as will be readily observed, cause the said tie rod or stretcher to stretch. The tie rods or stretchers support the timbers, lagging or forepoling, which is disposed parallel with the length of the room or heading, and which timbers in turn support the roof of the room, as will be plainly observed in the drawings.

This invention comprises further objects and combinations of elements which will be hereinafter more fully described, shown in the accompanying drawings, and the novel features thereof will be pointed out by the appended claims.

The features and elements and the arrangement thereof, for accomplishing the objects of this device or apparatus, may be changed and varied, that is to say, in a practical application of the invention, with an understanding that the changes and variations accruing from said application are limited to the scope of the appended claims.

To obtain a full and correct understanding of the details of construction, combinations of features, elements and advantages, reference is to be had to the hereinafter set forth description and the accompanying drawings in connection therewith, wherein

Figure 1 is a transverse section of a room, heading or a portion of a mine, showing the improved supporting device disposed therein, for supporting the roof measures. Fig. 2 is a sectional view on line 2-2 of Fig. 1, lon-

gitudinally therethrough, illustrating the uprights, standards or posts in elevation, as well as illustrating the timbers, lagging or forepoling, for supporting the roof of the room. Fig. 3 is a detail perspective view of one end of one of the tie rods. Figs. 4, 5 and 6 are plan views of different forms of tie rods, upon which the lagging or forepoling is disposed.

10 Like reference characters are utilized for indicating corresponding features and elements throughout the several views of the accompanying drawings.

In regard to the accompanying drawings, 15 wherein similar reference characters indicate corresponding parts in the several illustrations, by figures, 1 designates a room or heading which is disposed substantially at right angles to the mine shaft, as clearly shown in

20 Figs. 1 and 2; positioned within this room or heading, and adjacent to the longitudinal side walls, and substantially from two to four feet apart, are standards or posts 2, which diverge outwardly from one another, at their

25 upper portions, the purpose of which is hereinbefore set forth. The upper ends of these standards or posts are beveled, as at 3, which beveled portions engage the members 4, which are also inclined so as to correspond with the 30 bevel of the standards, and which members 4 are forced slightly inward, or embedded in the corner of the room, which is formed by the roof of the room and the side walls thereof, so that when the said standards or posts are 35 placed under the same and forced outwardly at their lower portions, a wedging action is provided, and together with the tie rods or stretchers, a very efficient support is provided, comprising strength and durability.

40 Spanning the room, heading or mine, and adjacent to its roof are tie rods or stretchers 5, which are disposed transversely thereof, and are connected to the standards or posts, as clearly shown in Figs. 1 and 2. These tie

45 rods or stretchers are provided with loops 6 at each end thereof, and which engage the circumference of the standards or posts, adjacent their upper ends, as will be clearly evident. To hold the tie rods or stretchers

50 in close proximity to the roof, and to prevent the same, to a certain extent, from slipping, wedges 7 are provided which are inserted within the loops and adjacent the circumference of the standards or posts, as 55 clearly shown in Fig. 1; these wedges are held in their places by friction, as a rule, but if desired, a spike or other means 8 may be driven into the standards or posts, and beneath the wedge, so as to prevent downward 60 displacement thereof, as will be clearly evident.

The tie rods or stretchers, as shown in Figs. 1 and 2, support timbers, lagging or forepoling 9, which in turn supports the roof 65 measures, as will be clearly manifest. The

drawings illustrate several different forms of tie rods or stretchers; in Fig. 4, the applicant has illustrated a cable bent upon itself, so as to form loops 10 and 10^a, and which are held in the form of loops by two 70 different forms of devices 11 and 12; the device 11 is merely an elliptical shaped ring which is slipped upon the cable, before the loop 10^a is formed. The body portion 13 and the end portions 14 of the cable are securely held together and parallel with one another, by means of staples 15, which forms the device 12; the ends of these staples 15 are provided with registering apertures 16, through which bolts 17 are inserted, and to 80 the threaded ends of which nuts 18 are applied, so as to bind the portions 13 and 14 together.

In Fig. 5 the tie rod is somewhat differently formed, as shown; the loops are formed 85 by bending the rod upon itself, and the free ends of said rod are coiled about the body portion of the rod, as at 19, and the extreme ends, as at 20, are formed into hooks which are engaged by an elliptical shaped ring 21. 90 In this form of tie rod, the same is made of solid material. In Fig. 6, the tie rod is similar to that shown in Fig. 5, with the exception that the free end portions are merely coiled about the body portion of the rod, as 95 shown at 22, thus leaving a single thickness of rod between the end portions.

From the foregoing, the essential features, elements and the operation of the device, together with the simplicity thereof, will be 100 clearly apparent.

Having thus fully described the invention, what is claimed as new and useful by the protection of Letters Patent, is;

1. In a roof support for mines, a plurality 105 of standards arranged in opposite rows, timber-supporting means connecting opposite standards, and wedges to prevent downward displacement of said means.

2. In a roof support for mines, a plurality 110 of standards arranged in opposite rows, timber-supporting tie rods or stretchers connecting opposite standards, and wedges to prevent downward displacement of said tie rods or stretchers.

3. In a roof support for mines, a plurality 115 of standards arranged in opposite rows, tie rods or stretchers having loops engaging and connecting opposite standards, timbers supported by said tie rods or stretchers and means inserted in said loops to prevent downward displacement of the tie rods.

4. In a roof support for mines, a plurality 120 of standards arranged in opposite rows, tie rods having loops engaging and connecting opposite standards, timbers supported by said tie rods, and wedges inserted in said loops to prevent downward displacement of the tie rods.

5. In a roof support for mines, a plurality 125

of standards arranged in rows and oppositely disposed so as to diverge outwardly at their upper portions and adjacent the longitudinal walls of the mine, tie rods or stretchers connecting opposite standards and provided with loops to engage the circumference of the standards, said tie rods having means for holding the loops properly formed, wedges to be inserted in said loops and engage said standards to prevent downward displace-

ment of the loops and timbers supported by said tie rods or stretchers for supporting the roof of the mine.

In testimony whereof I have signed my name to this specification in the presence of 15 two subscribing witnesses.

FREDERICK C. KEIGHLEY
